KNIFE SHARPENER

Floyd O. De Millar, Warwick, R. I.

Application June 5, 1943, Serial No. 489,848

2 Claims.

(Cl. 51—111)

The present invention relates to knife sharpener apparatus and has particular reference to a knife sharpener construction suitable for household use.

The principal object of the invention is to provide a household knife sharpener which sharpens a knife blade transversely with respect to the cutting edge and therefore imparts a honed edge.

Another object of the invention is to utilize two complementary grinding disks which have bevelled grinding edges and are mounted so as to position the grinding edges transversely to a knife edge.

An additional object of the invention is to provide an operating mechanism for causing two complementary grinding disks which are mounted to an angle to each other to rotate in unison.

Still another object to provide a compact knife sharpening device which is made of a small number of readily manufactured and assembled parts.

With the above and other objects and advantageous features in view, the invention consists of a novel arrangement of parts more fully described in the detailed description following, in conjunction with the accompanying drawing, and more specifically defined in the claims appended thereto.

In the drawing,

Fig. 1 is a top plan view of the assembled knife sharpener;

Fig. 2 is a front elevation thereof;

Fig. 3 is a side view of Fig. 4;

Fig. 4 is a section on the line 4—4 of Fig. 2; and

Fig. 5 is an enlarged sectional detail showing the positions of the grinding disks when sharpening a knife blade, the knife blade being indicated by dotted lines.

It has been found desirable to utilize a household knife sharpener which has two grinding disks so mounted that they present a plurality of grinding surfaces directed across the knife blade to be sharpened, the disks rotating in unison and contacting the sides of the knife blade so that the sharpening is transverse to the knife blade edge and not longitudinal. To this end, I provide two grinding disks which have bevelled annular edges equipped with complementary grinding faces, the faces being angularly disposed in relation to the disks so that they present parallel grinding areas to an interposed knife blade, the disks being mounted to rotate at a slight angle to each other.

Referring to the drawing, the novel household sharpener 10 includes a frame 11, preferably

made of stamped metal, and having a base 12 adapted to be mounted on a table or wall portion and provided with suitable openings 13 for receiving retaining screws or the like. The frame has two upstanding arms 14 which terminate in horizontal alignment to receive cylindrical journals 15, the journals being preferably secured to the upper ends of the arms, although if desired they may be formed integral therewith. The angular displacement of the arms and journals in a horizontal plane is shown in Fig. 1. A pair of complementary grinding disks 16, 17 are provided, each disk being mounted on a rotatable support. A preferred construction of support is shown in Fig. 4, and includes a plate member 18 mounted on the back of the disk and having a hub portion 19 from which an axial shaft 20 extends to be rotatably received in the journal 15. The hub portion is recessed to receive a flanged bushing 21 which extends through a central opening 22 in the disk and is locked in place by a back plate 23 and a retaining bolt 24. The face of the bushing flange is preferably hexagonal, as illustrated in Fig. 3, and is slit to receive one end of a spiral coil 25, the construction thus providing a universal connection between the two disks through the medium of a spiral coil so that rotation of one disk simultaneously causes rotation of the other disk.

As shown in Fig. 4 an adjusting screw 26 extends through a threaded opening in the end wall of one journal and contacts the end of the shaft therein; a handle 27, see Fig. 2, is secured to the end of the other shaft through a suitable opening 35 in the end of the other journal, whereby manual rotation of the handle produces a positive rotation of both disks.

Referring now to Fig. 5 the disk 16 is preferably provided with a plurality of spaced annular grinding edges 28, 29 having their grinding surfaces 30 angularly disposed with respect to the plane of the disk so that they are in parallel relation to a knife blade (indicated in dotted lines), when the disk axis is mounted at an acute angle to the plane of the knife blade, as illustrated. The second disk 17 is preferably mounted at a complementary acute angle to the plane of the knife blade, and has an angular grinding edge 31 with its grinding surface 32 positioned in parallel relation to the knife blade, and preferably engaging the knife blade edge at a point intermediate the grinding surfaces of the first disk, whereby a staggered grinding effect is produced.

The above construction is thus simple to manufacture and to assemble, and comprises two an-

gularly disposed disks which are simultaneously rotatable and which have their grinding surfaces in the plane of the knife blade at the area of contact with the knife blade, whereby the sharpening is accomplished by a grinding action transverse to the plane of the knife blade to produce a honing effect on the knife blade edge.

While I have described a specific constructional embodiment of my invention, it is obvious that changes in the size and relation of the parts and in their construction and assemblage may be made to suit the requirements for different types of knife sharpeners, without departing from the spirit and the scope of the invention as defined in the appended claims.

I claim:

1. A blade sharpener comprising a base member having two spaced journals, two grinding disks each having a support including an axial shaft, said shafts being rotatably mounted in said journals and angularly disposed with respect to each other whereby said disks are peripherally

adjacent at one point, a universal connection between said disks consisting of a spiral spring having its ends locked centrally to each disk, means for rotating one disk, whereby said disks rotate simultaneously, and means for axially adjusting the shaft of the other disk.

2. A blade sharpener comprising a base member having two spaced journals, two grinding disks each having a support including an axial shaft, said shafts being rotatably mounted in said journals and angularly disposed with respect to each other whereby said disks are peripherally adjacent at one point, a universal connection between said disks consisting of a spiral spring having its ends locked centrally to each disk, means for rotating one disk, whereby said disks rotate simultaneously, and means for axially adjusting the shaft of the other disk, said disks having relatively staggered annular grinding edges shaped to provide parallel grinding areas at the point of adjacency.
